United States Patent Office.

AUSTIN A. SMITH, OF SENECA FALLS, NEW YORK.

Letters Patent No. 77,115, dated April 21, 1868; antedated April 11, 1868.

IMPROVEMENT IN LAMP-SHADES.

The Schedule referred to in these Letters Patent and making part of the same.

TO ALL WHOM IT MAY CONCERN:

Be it known that I, AUSTIN A. SMITH, of Seneca Falls, in the county of Seneca, and State of New York, have invented a certain new and useful Improvement in Lamp and Gas-Light Shades; and I do hereby declare that the following is a full and exact description thereof, reference being had to the accompanying drawings, making part of this specification.

Figure 1 is a plan of my improved shade.

Figure 2, an elevation of the same.

Figures 3 and 4, diagrams showing the spring-joint for holding the panels in position.

Like letters of reference indicate corresponding parts in all the figures.

My invention consists in forming the sides of a lamp or gas-light shade of ordinary form into numerous panels or sections situated upright between the rims, and turning horizontally or angularly so as to open any portion, on any side, to allow the passage of light; also, in the employment of a joint, consisting of two spring-wires resting in a square or oblong slot, and operating in such a way as to hold the panel either open or closed, as hereinafter set forth.

As represented in the drawings, the skeleton of the shade is composed of top and bottom rims, A A, braces a a, connections b b, and the usual ring, B, or its equivalent, for connecting the shade with the chimney of the lamp, or with the tip of the gas-burner. The shade is in the usual form of lamp-shades, being the frustum of a cone.

Between the rims A A are situated numerous upright panels or sections, C C C, resting on joints or hinges so as to turn or swing horizontally or angularly, and fitting closely together when shut. These panels form the shade proper. They may be made of pasteboard, thin metal, or any other suitable material. They may also be embossed, stamped with any ornamental design, or made semi-transparent, if desired.

The joint or hinges g g may be arranged at any position, so that the panels will turn horizontally or angularly, but I prefer to locate them centrally at top and bottom. I make one set of the joints (preferably the upper) of two expanding spring-wires, f f, secured to the panel, and resting in a square or oblong slot, d, made in the rim A. The notches or elongations of this slot are so arranged that when the wires expand in them, the panel will stand either in an open or closed position.

It is my object, in this construction, to preserve the usual circular, conical form of the shade, which is the only one adapted to general use, and at the same time provide numerous panels, that can be opened or closed at pleasure on any side, and can be graduated to allow the passage of any desired degree of light.

I am aware that it has before been proposed to use sliding screens with the shade, as in Patent No. 39,438, but in this case only a very limited number of slides can be employed, since as much space is covered by the slide in opening, as the space that is opened. I am also aware that it has been proposed to employ a shade with four hinged flaps, that turn up vertically, as in Patent No. 48,632, but in this case the usual form of the shade is lost, and one substituted in the form of a truncated pyramid, which is not adapted to ordinary use. When the flaps are turned up they obstruct the passage of light upward.

In my shade I obviate the disadvantages of these. It is of the usual form, and adapted to all ordinary uses. I can set the panels all open, if desired, so as to form no obstruction to the light at all, or I can open one or more at any point, independent of the others. I can graduate the amount of space opened, from the single small panel to any desired number, and when opened there is no obstruction to the upward passage of light.

The spring-wires forming the upper joint serve as a very convenient means of holding the panels either closed or opened. A slight touch of the fingers will turn the panel sufficiently to receive motion by the spring, when the panel turns automatically to the desired position.

I do not claim a shade with sliding screens closing the openings for the passage of light, neither do I claim a shade with hinged flaps turning up vertically; but

What I claim as my invention, and desire to secure by Letters Patent, is—

1. As a new article of manufacture, a lamp or gas-light shade of usual form, composed of numerous upright panels or sections, C C C, situated closely together to form a screen, and turning horizontally or angularly on suitable joints, the whole arranged and operating so that any number of said panels may be opened at any desired position, and the passage of light may be graduated, as herein set forth.
2. Forming one or both of the joints of the panels, of spring-wires *ff*, resting in the square or oblong slots *d*, operating as and for the purpose specified.

In witness whereof, I have hereunto signed my name in the presence of two subscribing witnesses.

A. A. SMITH.
